UNITED STATES PATENT OFFICE.

FRANK BURJANEK, OF CHICAGO, ILLINOIS, ASSIGNOR TO HERHOLD CHAIR CO., OF CHICAGO, ILLINOIS, A CORPORATION OF ILLINOIS.

DESIGN FOR A BENT-STOCK CHAIR.

54,375.

Specification for Design.

Patented Feb. 10, 1920.

Application filed February 16, 1918. Serial No. 217,709. Term of patent 14 years.

To all whom it may concern:

Be it known that I, FRANK BURJANEK, a citizen of the United States, residing at Chicago, county of Cook, and State of Illinois, have invented a new, original, and ornamental Design for Bent-Stock Chairs, (Case D,) of which the following is a specification, reference being had to the accompanying drawings, forming a part thereof.

The drawing is a perspective view of the chair showing my new design.

I claim:

The ornamental design for a bent stock chair substantially as shown.

In testimony whereof I have hereunto signed my name in the presence of two subscribing witnesses.

FRANK BURJANEK.
